UNITED STATES PATENT OFFICE.

WILLIAM FORNER YOUNG, OF PHILADELPHIA, PENNSYLVANIA, ASSIGNOR
OF ONE-HALF TO HENRY S. DAVIS, OF SAME PLACE.

CAR-FENDER.

SPECIFICATION forming part of Letters Patent No. 600,601, dated March 15, 1898.

Application filed February 16, 1897. Serial No. 623,607. (No model.)

To all whom it may concern:

Be it known that I, WILLIAM FORNER YOUNG, a citizen of the United States, residing at Philadelphia, in the county of Philadelphia and State of Pennsylvania, have invented a certain new and useful Improvement 5 in Car-Fenders, of which the following is a specification.

My invention relates to a new and useful improvement in car-fenders adapted to both project in front of the body of the car as well as that of the trucks thereof, and has for its object to provide safety for life and limb to persons standing near or approaching street-cars and also to protect the car from injury 15 from contact with other parts. This is to be done by means of fenders or wheel-guards attached to and arranged about the car adapted for the use designed.

With these ends in view this invention consists in the details of construction and combination of elements hereinafter set forth, and then specifically designated by the claim.

In order that those skilled in the art to 25 which this invention appertains may understand how to make and use the same, its construction and operation will now be described in detail, referring to the accompanying drawings, forming a part of this specification, in 30 which—

Figure 1 represents a car having my improvements applied thereto; Fig. 2, a detail view of my improvements, the car being omitted; and Fig. 3, a plan view of the front fender, the sections thereof lying in the same 35 horizontal plane.

The front fender consists of a vertical or nearly vertical rod or standard *a*, made, preferably, of light piping, connecting with the 40 car-sill by means of an iron bracket or brace-straps *c* and bolts. It is curved forward at its lower end, near which it is hinged at *e* with a horizontally-projecting frame *d*, which declines toward the ground at its foremost end, 45 which also curves in front of the car and across the track. It is of similar construction on both sides. This hinged extension *d* is connected with the vertical standard *a* by means of a 50 chain *f*, having links *h* for adjustment of its elevation or distance from the ground at the forward point. Below the intersection of the

chain *f* with the vertical rod *a* is placed an adjustable spring coupling or link *g*, which engages with a link in the chain *f* and connects with the vertical rod *a*. The spring of 55 the link draws the extension-frame *d* slightly up from the ground and makes a spring-tension upon the chain *f*, the purpose of which is twofold: first, to allow the fender to pass over the ordinary level of the street, but to 60 be raised by objects striking it from underneath, and, second, to allow it to be pressed very nearly to the ground by objects striking it from above or in front, thus preventing such objects from getting under the car. 65

The entire front frame *a d* is filled with net or mesh work, preferably of cord or rope, with very much smaller meshes in the front part of the extension *d* than elsewhere, as shown, for the purpose of arresting with the least possible 70 injury the person who might fall into it, the finer woven parts serving to prevent the hands or feet of children from passing through and being injured against the ground or stones. 75

My invention consists, likewise, of a rod or pipe frame filled with network *L*, coming in front of the wheels under the car and extending on both sides of the trucks far enough to protect the wheels. It is attached to the bumper-bar *b* at the front by means of an adjustable clevis *i* and in the rear to the side of the trucks by means of a gage and brace *k*, as illustrated in Fig. 1, and this gage and brace consists of a curved bar *k*, attached to the 80 side of the truck-frame, while two arms *l* project upward from the fender-frame and have holes *m* therein, by means of which these arms are put into engagement with the curved ends of the brace in any suitable manner, 85 such as by passing a pin *n* therethrough, and by means of a number of these holes a vertical adjustment is had. This device provides for its proper adjustment according to required height. 95

In all the figures is shown a rope *L* at their lower or base line. This rope is laid in the concave surface of metal—for example, a half-pipe—which serves to hold it rigidly in position and by which it is joined to the other 100 part of the metallic frame.

The novelty of my invention consists in the

manner of attaching the wheel-guard, which is placed in front of and along the sides of the wheels and serves to protect the wheels and machinery from damage and also persons from possible hurt.

5 I claim as new and as my invention—

In combination, a suitable frame adapted to extend to the front and sides of a street-car, a clevis securing said frame in front to 10 the bumper-bar, and a gage securing it at the rear to the truck-frame, said gage consisting of a curved bar secured to said truck-frame,

two arms having holes therein projecting upward from the fender-frame, and pins adapted to pass through the holes in the arms, as 15 and for the purpose described.

In testimony whereof I have hereunto affixed my signature in the presence of two subscribing witnesses.

WILLIAM FORNER YOUNG.
